UNITED STATES PATENT OFFICE.

ARTHUR H. JOHNSON, OF RAHWAY, NEW JERSEY.

BRIDGE-CO尤LING FOR SWITCH-RODS, &c.

SPECIFICATION forming part of Letters Patent No. 415,388, dated November 19, 1889.

Application filed February 27, 1889. Serial No. 301,300. (No model.)

To all whom it may concern:

Be it known that I, ARTHUR H. JOHNSON, of Rahway, in the county of Union and State of New Jersey, have invented a certain new 5 and useful Improvement in Bridge-Couplings for Switch-Rods, &c., of which the following is a specification.

Where railroad-tracks cross bridges, and it is desired from the bridge itself to manipulate switches, signals, &c., difficulty has been experienced in coupling and uncoupling the portions of the operating devices upon the bridge and upon the abutments. This difficulty has arisen from the fact that variations 15 in temperature will cause the coupling-pieces to be separated more or less from each other, so that a perfect joint cannot be obtained. It is the object of my improvement to overcome this difficulty.

20 In carrying out my improvement I employ coupling-pieces comprising members of a clutch, the members when together forming a coupling-piece which may be rotated.

In the accompanying drawings, Figure 1 is 25 a diagrammatic view showing the draw-bridge, railroad track and switches, together with coupling-pieces, and mechanism for operating them embodying my improvement. Fig. 2 is a side elevation of a coupling-piece 30 embodying my improvement and showing certain means for rotating the same. Fig. 3 is an end view of one of certain wheels employed therein. Fig. 4 is a side elevation showing a modification. Fig. 5 is a plan view of the 35 same. Figs. 6 and 7 are detail views, the one in plan and the other in section, showing means for locking the coupling-pieces against rotation under certain conditions. Fig. 8 is a sectional elevation on the line xx , Fig. 4, and 40 showing a bearing for one of the members of a coupling-piece.

Similar letters of reference designate corresponding parts in all the figures.

A designates a draw-bridge, and B the abutments therefor. Upon the draw-bridge I have shown a switch-stand C, from which switches D upon the abutments B may be manipulated, and also from which coupling-pieces E may be operated. From the switch-stand C 45 extends rod a , connected by a bell-crank lever to a rod a' . At the opposite ends of the rods a' there are bell-crank levers which connect with rods a^2 , the latter being connected at their other ends with members a^3 of the coupling-

pieces. By operating a lever, which may be of 55 the ordinary kind, at the switch-stand C both of the members a^4 of the coupling-pieces may be moved longitudinally to engage or disengage other members a^5 of the coupling-pieces, which latter members are located upon the 60 abutments for the bridge. From the switch-stand C also extend rods a^6 , which rods are connected by means of bell-crank levers with rods a^7 , extending to the members a^4 of the coupling-pieces. By manipulating suitable 65 levers at the switch-stand the rotation of the members a^4 of the coupling-pieces may be effected. The members $a^4 a^5$ of the coupling-pieces comprise at their adjacent extremities clutch members $a^8 a^9$. In all the examples of 70 my improvement shown these clutch members are disunited and the parts occupy a position in which the draw-bridge may be freely swung. It is to be understood, however, that when the draw-bridge occupies the position shown 75 in Fig. 1 and trains are to be passed over the bridge the clutch members will be united. When united, the rotation of the members a^4 of the coupling-pieces will be transmitted to the members a^5 thereof. From the members 80 a^5 motion is transmitted through suitable mechanism comprising rods $a^{10} a^{11} a^{12}$ and intermediate bell-crank levers to the switches D in order to throw the latter.

In Fig. 2 I have shown suitable means for 85 causing the rotation of the members of the coupling-pieces. The rods $a^7 a^{10}$ will in this instance be connected, respectively, to ordinary bell-crank levers to which would be connected rods $a^{13} a^{14}$, which rods would extend 90 parallel to the track in order to impart rotary motion to wheels $b b'$, also arranged parallel to the track and journaled in suitable bearings b^2 upon the bridge and the abutments, respectively. The wheels $b b'$ have upon one 95 side beveled gear-teeth, which beveled gear engages beveled pinions $b^3 b^4$. The beveled pinion b^3 has a feathered connection with the member a^4 of the coupling-piece, so that the said member may be slid freely through the pinion b^3 , but so that the rotation of said pinion will cause the rotation of the said member a^4 .

When the clutch members $a^8 a^9$ have been brought together by the longitudinal movement of the member a^4 of the coupling-pieces and the rod a^{13} has been moved lengthwise, of course a rotary motion will be imparted to the 105

wheel b , which motion will be transmitted through the clutch members and the pinion b^4 and wheel b' to the rod a^{14} , from which motion will be transmitted to the switch D , with which 5 it co-operates.

I have shown in dotted outline in Fig. 2 that chains passing about the wheels b b' may be employed to rotate said wheels. These 10 manner, and I do not deem it necessary to illustrate means for accomplishing their movement or their connections with the switch mechanism.

In Fig. 3 I have illustrated more particularly one of the wheels b b' , adapted to receive chains.

In Figs. 4 and 5 I have more particularly illustrated the form of coupling-piece and its operating mechanism illustrated in Fig. 1.

20 In this form of the improvement the rotary motion is imparted to the member a^4 of the clutch by means of an arm c , mounted upon the said coupling-piece member, so as to transmit rotary motion thereto, but so that 25 the said member may slide freely through it. The arm c is connected at its lower extremity with the rod a^7 . A similar arm c' is rigidly mounted upon the member a^5 of the coupling-piece, and is connected at its lower extremity 30 with the rod a^{10} . I have illustrated in this form of the device in dotted outlines in Fig. 4, and more particularly in Fig. 8, that the member a^4 of the clutch may rest in yielding 35 bearings d . The yielding bearings d have secured upon them upon their upper and lower sides guide-rods d' , extending through suitable apertures in the supports d^2 , in which the bearings are mounted. The member a^4 may therefore rise and fall within the supports d^2 in order to accommodate variations 40 in the level of the bridge adjacent to the abutments which may be occasioned by the passage of trains from one to the other. By this means danger of breakage of the coupling-pieces is avoided.

45 When from any cause great strain is brought to bear upon the coupling-pieces, tending to rotate them, if the clutch members be suddenly drawn apart, rotary motion to a certain extent of the members a^4 a^5 might ensue, which might partially throw a switch or prove otherwise objectionable. To avoid this I have shown in Figs. 6 and 7 means for locking the members a^4 a^5 of the coupling-pieces 50 when the clutch members are separated. Upon the member a^4 is formed a rib e , adapted to be slid to and fro in a suitable groove formed in one of the bearings for the said member. This rib is only of such extent, 55 however, that when the clutch members are united the rib will be out of said groove and the said member might therefore be freely rotated. When disunited, however, the rib is within the groove, and consequently prevents 60 the rotation of the member.

65 Referring to the member a^5 of the clutch, I have shown a locking-piece f , having a por-

tion extending longitudinally through a suitable socket f' formed in said member. Upon the rear end of said locking-piece is a shoulder or projection f^2 . Within the socket f' , and to the rear of the shoulder f^2 , is a coil-spring f^3 , the tendency of which is to always force the locking-piece f forward, so that the shoulder f^2 will extend into a notch f^4 formed 70 to receive it in one of the bearings for said member. When the members of the clutch are united, the member a^5 will contact with the locking-piece f and force it rearwardly against the resistance of the spring f^3 , thereby removing the shoulder f^2 from the notch f^4 . The coupling member a^5 may then be 75 freely rotated. When the member a^5 of the clutch is withdrawn, however, the locking-piece f will follow by its movement, and the shoulder f^2 will become engaged with the notch f^4 and cause the locking of the coupling member a^5 against rotation.

80 It is to be understood that the members a^5 of the clutch are of such extent lengthwise that they will not be withdrawn from engagement by contracting of the bridge or the clutch members themselves, due to low temperature, or, in other words, that under all variations in temperature there will be a free 85 play between the members of the clutch.

90 Of course I do not wish to be understood as limiting myself specifically to the means shown and described for operating the switches or uniting or disuniting the coupling-pieces; nor do I wish to be understood as 95 limiting myself to the means shown and described for imparting rotary motion to the coupling-piece members, as obviously many other means might be devised for accomplishing these results.

100 What I claim as my invention, and desire to secure by Letters Patent, is—

1. A bridge-coupling for railway-switch and similar systems, comprising coupling-pieces one member of which is longitudinally movable and is rotated by the operation of the system to impart rotary motion to the other member, substantially as specified.

115 2. A bridge-coupling for railway-switch and similar systems, comprising coupling-pieces one member of which is longitudinally movable and is rotated by the operation of the system to impart rotary motion to the other member and yielding bearings for one 120 of said members, substantially as specified.

125 3. A bridge-coupling for railway-switch and similar systems, comprising coupling-pieces one member of which is longitudinally movable and is rotated by the operation of the system to impart rotary motion to the other member and locks for preventing the rotation of said members when the members are separated, substantially as specified.

ARTHUR H. JOHNSON.
